UNITED STATES PATENT OFFICE

SAMUEL WERNER, OF RUTHERFORD, NEW JERSEY; EUGENE WERNER ADMINISTRATOR
OF SAID SAMUEL WERNER, DECEASED

CAP

Application filed September 8, 1930. Serial No. 480,340.

This invention relates to caps.

Many different expedients have been adapted to provide a cap that is adjustable as to size. Such expedients, however, have not been particularly successful. For instance, elastic inserts have been used but these are objectionable since they cause a pressure against the head of the wearer. Snap fasteners that can be fastened in a plurality of positions have also been tried out but in this form of construction folds, gathers or puckers have been formed which detract from the appearance of the cap and from the comfort of the wearer.

This invention has for its object to provide a cap with means for permitting adjustment of the cap as to size and so arranged that no puckers or gathers are formed and no elastic pressure against the head of the wearer is caused to take place.

Another object of the invention is to provide an adjustable cap having a sweat band that is yieldable and can be lengthened or contracted but will retain its shape in all positions of adjustment.

Further objects of the invention will appear from the following specification taken in connection with the drawings, which form a part of this application, and in which

Fig. 1 is a bottom view in perspective showing a cap constructed in accordance with the invention;

Fig. 2 is a front elevation of the cap shown in Fig. 1, the front of the cap being raised to show the adjusting means;

Fig. 3 is a sectional elevation through the sweat band and adjacent parts;

Fig. 4 has an enlarged front elevation taken substantially on line 4—4 of Fig. 1; and

Fig. 5 is an enlarged detailed elevation showing the construction of the adjustable sweat band.

The invention briefly described consists of a cap having a portion or, if desired, all of the sweat band formed of yieldable non-elastic material adapted to be lengthened or contracted and to retain its shape in adjusted position. Means is also provided for adjusting the circumference of the sweat band so that a single cap can be used to satisfy the

requirements for a plurality of sizes. In the particular form of the invention shown a sweat band is formed of braided material such as leather, the strands of the braided material being biased.

In the form of the invention illustrated in the drawings the cap comprises a body portion 10, a visor 11 and an annular band 12.

In the embodiment of the invention shown in the drawings the sweat band comprises a pair of sections 13 and 14. The section 13 is preferably formed of leather and section 14 is also formed of leather but is constructed from a plurality of strips 15 and 16 which are braided and extend diagonally or are biased.

As shown in Fig. 4, the upper and lower edges of the annular band 12 are turned inwardly, the upper edge being stitched to the body of the lower portion and the lower edge being folded back and stitched to itself and also being connected to the sweat band. The front portion of the band 12 is cut away, as shown at 17, and 18, and a tape 20 is placed in the annular opening or channel formed between the sweat band and the band portion 12. One end of the tape may be provided with a clip 21, the other end 22 being passed beneath the clip and adjustably secured thereby. If desired, the tape may be provided with indicia 23 to indicate the various sizes.

The braided section 14 of the sweat band is preferably stitched, as shown at 25 and 26, at the longitudinal edges thereof and a beading 27 is stitched to the edges. The beading is disposed between the body portion 10 and the annular band 12 and along the lower edge of the sweat band is disposed between the lower edge of the band 12 and the sweat band.

Particular attention is called to the braided or biased construction of the sweat band section 14.

In order to adjust the cap to any desired size within the range of sizes for which a cap is adapted the end 22 of the tape is clipped to the other end of the tape so that the mark 95 indicating the desired size is disposed beneath the clip. By grasping the sweat band at opposite sides and pulling the band longitudinally the yieldable section 14 will shape itself to the desired size or to the size formed by the

length of the tape 20. This adjustment is permitted by reason of the braided or stranded construction and the section 14 can be lengthened or contracted in the manner described to provide a plurality of different sizes. Furthermore, when this section has been adjusted the sweat band will remain flat and will not be puckered or gathered. It is assumed that the band 12 is formed of material woven loosely or in such a way as to permit the band to stretch or contract in conformity to the length of the section 14. In other words, the material from which the band 12 is formed has a limited amount of "give".

From the foregoing description it will be evident that a simple, practical and adjustable cap structure has been designed and that the construction described will admit adjustability as to size without causing the sweat band to be gathered, puckered or pulled out of shape.

Although one specific embodiment of the invention has been particularly shown and described, it will be understood that the invention is capable of modification and that changes in the construction and in the arrangement of the various cooperating parts may be made without departing from the spirit or scope of the invention, as expressed in the following claims.

What I claim is:

1. A cap comprising a body portion and a lower edge having an annular pocket, the inner wall of the pocket consisting of a sweat band having a section thereof formed of a flexible, non-elastic braided strip of material adapted to be lengthened or contracted, and means in said pocket for adjusting the length thereof.
2. A cap comprising a body portion and a lower edge having an annular pocket, the inner wall of the pocket consisting of a braided sweat band formed of strips of leather, crossing each other and disposed at an angle to the edge of the cap and secured at their ends to the margins of the pocket.
3. A cap comprising a body and an annular pocket at the lower edge thereof, the inner wall of the pocket being formed by a sweat band secured along its upper and lower edges to the other wall of the pocket, a portion of the inner wall consisting of a biased strip of flexible, non-elastic material adapted to lengthen or contract, and means in the pocket for adjusting the length of said portion of the sweat band.

SAMUEL WERNER.
